UNITED STATES PATENT OFFICE.

ROBERT GRACEY, OF ALLEGHENY, ASSIGNOR TO R. GRACEY & SONS, OF PITTSBURG, PENNSYLVANIA.

SHAFTS FOR VEHICLES.

SPECIFICATION forming part of Letters Patent No. 427,507, dated May 6, 1890.

Application filed June 28, 1889. Serial No. 315,934. (No model.)

To all whom it may concern:

Be it known that I, ROBERT GRACEY, of Allegheny, in the county of Allegheny and State of Pennsylvania, have invented a new and useful Improvement in Shafts for Vehicles, of which the following is a full, clear, and exact description.

My invention relates to an improvement in shafts for vehicles; and it consists in the devices hereinafter more fully explained.

I will now describe my invention so that others skilled in the art may manufacture and use the same, reference being had to the accompanying drawings, forming part of this specification, in which—

Figure 1 is a plan view of my improvement. Fig. 2 is a detached detail view of a part of the same. Fig. 3 is a modification. Fig. 4 is a detached view of one form of spreader or separator. Fig. 5 is a view of a modification of the same.

Like letters of reference indicate like parts in each.

Heretofore in the construction of tubular and other shafts great trouble has been experienced in forming tight and sure connections between the shafts and the cross-bars. These shafts and cross-bars, being composed either wholly or partially of tubular metal, are liable in use to become loose and disconnected.

The object of my invention is to provide means by which the parts will be tightly secured to each other, so as to prevent rattling or loosening, and to this end, instead of employing a single tubular cross-bar, I employ two bars, both of which are connected with the shafts and are at their middle portion connected or brought in contact with a separator or spreading-block, by which means any twisting or loosening action imparted in use to one bar is counteracted by the other.

In the drawings, *a* represents the shafts, and *b* *c* the two cross-bars. These bars may be of wood or metal, as is desired, and the shafts may be formed either of tubular metal or of wood or other material, the only difference being that in the case of the tubular

shaft a metallic coupling *d* is employed, by means of which the cross-bars are either 50 welded, riveted, or connected by a screw-connection, or in other ways, with the shafts, while in the case of a wooden shaft a coupling *e* is employed, which is bolted to the shaft, and to this coupling-piece the cross-bars are connected in a like manner. Where it is desired to secure the singletree to the cross-bars, I employ the spreader or separator shown in Fig. 4, this separator being provided with a suitable socket for the singletree-bolt. Where, however, there is no connection desired between the cross-bars and the singletree, a plain spreader or separating-block *f* may be employed, as shown in Fig. 5.

The advantages of my improvement are that by means of the double cross-bars all tendency to distortion or loosening of the parts is prevented, and the shafts are rendered perfectly rigid and secure.

I do not desire to limit myself to any special means of securing the double cross-bars to either the tubular metal shaft or the wooden shaft, as this is a matter within the discretion of a skilled mechanic.

Having thus described my invention, what I claim, and desire to secure by Letters Patent, is—

1. As an improvement in shafts for vehicles, the combination of the shafts, two or more bars permanently connected with the shafts, and a spreader or separating-block situated between the two bars, substantially as and for the purposes described.

2. As an improvement in shafts for vehicles, the combination of the shafts, two or more cross-bars, and a separating-block arranged between the two bars and provided with a singletree-bolt socket, substantially as and for the purposes described.

In testimony whereof I have hereunto set my hand this 18th day of May, A. D. 1889.

ROBERT GRACEY.
